SHIP RAISING DEVICE

Diamond Diamantides, Massillon, Ohio

Application December 23, 1941, Serial No. 424,177

1 Claim. (Cl. 294—66)

This invention relates to ship raising devices, and has for one of its objects the production of a simple and efficient grappling means for gripping the sides of a sunken vessel or ship to facilitate the raising thereof.

A further object of this invention is the production of an efficient grappling element which may be suspended above the sides of a sunken ship, and which will automatically grip the sides of a ship under the bumper guard to firmly attach the grapple to the ship to facilitate the raising of the ship.

Other objects and advantages of this invention will appear throughout the following specification and claim.

In the drawing:

Figure 1 is a fragmentary side elevational view of the shipraising apparatus;

Figure 2 is a front elevational view;

Figure 3 is a perspective view of one of the grapples or grappling members.

By referring to the drawing, it will be seen that 10 designates a sunken ship which is provided with the usual overlapping plates 11 which structure is conventional with all ships. A series of pontoons 12 are used in connection with the invention. The pontoons 12 are filled with water and are sunken to the desired depth adjacent and above the sunken ship 10. Air lines 13 lead to the pontoons 12 for blowing the water from the pontoons 12 when it is desired to raise the sunken vessel.

A pair of grapples 14 are suspended from the pontoons 12 by a cable 15, as shown in Figure 2, so as to position one grapple of each pair on opposite sides of the ship 10. These grapples of each pair are tied together by the portion 16 of the line 15, extending from one grapple to the opposite grapple, as shown in Figure 2. Each grapple comprises a vertical portion 17 and an inturned right-angularly extending widened grapple foot 18 which is adapted to fit under the edge of one series of plates 11, as shown, while raising the ship 10. Each grapple 14 is also provided with an inwardly extending top arm 19 which is downwardly inclined, as shown in Figure 2. The arms 19 of the grapples 14 of each pair extend inwardly of the ship and toward each other. The inner end of each arm 19 is enlarged and is provided with an eye or apertured portion 20 through which the lower end of the supporting or suspending cable 15 passes for tying the grapples of the pairs together.

The upper ends of the cables 15 which con-

nect each pair of grapples are tied around the supporting pontoons 12, as shown, and two of these supporting pontoons are used for each pair of grapples, the grapples of each pair being connected by the transverse portion 16 of the cable 15, as shown in Figure 2. In Figure 1, the pontoons 12 are broken away to illustrate a series of pontoons within the small space permitted upon the drawing.

The operation of the device is as follows:

A series of pontoons filled with water are lowered to the desired position above the sunken vessel or ship. Pairs of grapples 14 in suitable number to suit the size of the ship to be raised are suspended from the pontoons 12 before lowering. Fifty or one hundred of these grapples may be used if desired. This apparatus is lowered until the grapples 14 reach a desired gripping position approximately the position shown in dotted lines in Figure 2, and the inwardly extending and downwardly inclined arms 19 will cause the grapples to assume this position. Water is then blown out of the pontoons 12 to make the pontoons buoyant and to provide lifting power. Compressed air is forced into the pontoons through the air lines 13 in the conventional manner. As the lifting power of the pontoons 12 increases, the inwardly extending arms 19 will be pulled upwardly by the cable 15 in the direction of the arrow shown in Figure 2, and the grapples 14 will automatically swing to a gripping position shown in full lines in Figure 2, so that the grapple feet 18 fit under the edges of the plates 11. As the pontoons 12 rise, the grapples 14, which grip the hull of the ship 10 as shown, will lift the ship to a point near the surface of the water where means are provided to float the ship.

It should be understood that I have provided a specially constructed grapple which may be used in any number desired for automatically gripping the sides of a sunken ship when a lifting pull is exerted upon the grapple or grapples, and after the grapples have been lowered to a grappling or contacting position with respect to the sunken ship 10.

It should be further understood that certain detail changes may be employed without departing from the spirit of the invention, so long as such changes fall within the scope of the appended claim.

Having described the invention, what I claim as new is:

A grapple of the class described comprising a body having an inwardly extending arm, said

arm having means at its inner extremity for engaging a suspending element, a depending portion secured to the outer extremity of said arm, a right-angularly extending widened grapple foot carried by the lower extremity of said depending portion, the grapple foot flaring from the depending portion outwardly toward the gripping face of the grapple foot to provide a wide gripping face for the grapple foot and to present a maximum lifting force along its inner edge for engagement with an object to be lifted,

5 said arm being inclined downwardly toward its inner end and being of greater length than said grapple foot and being adapted to force said foot into engagement with an object to be gripped thereby when a lifting force is exerted upon the inner end of said arm, and the weight of said arm being adapted to swing said foot to a disengaging position when a lifting force is released from the inner end of said arm.
